UNITED STATES PATENT OFFICE.

PHILIP MICHEL, OF STAPLETON, NEW YORK.

WINDOW-SHADE.

SPECIFICATION forming part of Letters Patent No. 245,197, dated August 2, 1881.

Application filed June 18, 1881. (No model.)

To all whom it may concern:

Be it known that I, PHILIP MICHEL, a citizen of the United States, residing at Stapleton, in the county of Richmond and State of New York, have invented new and useful Improvements in Window-Shades, of which the following is a specification.

This invention relates to that class of window-shades embodying a sheet-metal binding-strip; and it consists in a retaining strip or shoulder on the lower edge of the shade, for the reception of the binding-strip, the latter being bent or shaped transversely to engage the retaining strip or shoulder; also, in constructing the retaining-strip in sections, to save material and allow the shade to fold crosswise.

This invention is illustrated in the accompanying drawings, in which Figure 1 represents a side view, partly in section. Fig. 1* is a similar view, omitting the binding-strip. Fig. 2 is a cross-section on the line $x-x$, Fig. 1. Fig. 3 is a similar section on the line $y-y$, Fig. 1.

25 Similar letters indicate corresponding parts.

The letter A designates the shade, B the retaining strip or shoulder, and C the binding-strip.

The retaining-strip B is a fixture of the shade, in contradistinction to the binding-strip C, which is detachable, the retaining-strip being arranged on the lower edge of the shade. In this example the retaining-strip B is made of sheet metal, and it is secured by being bent to embrace the shade, and struck up at divers points, forming barbs d, which pass through the shade; but, if desired, the retaining-strip may be made of wood or other similar material, and secured in various other ways, which will readily suggest themselves to a skilled mechanic; or the retaining-strip may be formed by folding the lower edge of the shade on itself, thus increasing the thickness of the shade at that edge and forming a shoulder for the engagement of the binding-strip.

The binding-strip C is made of sheet metal, and is bent or shaped transversely in such a manner that its longitudinal edges approach

each other, leaving sufficient space between them to admit the shade, the body of this being adapted to embrace the retaining strip or shoulder, and when it is desired to adjust the binding-strip it is simply slid on the retaining strip or shoulder from either end thereof, thus engaging the same by means of lips e formed by its approaching edges.

The peculiar advantage gained by the use of the retaining strip or shoulder B is that the binding-strip requires no pressing or other tool-work in its attachment, allowing it to be ornamented in any desired manner without danger of defacing the ornamentation, and that the binding-strip is thus rendered detachable.

The retaining-strip B is made in sections which are independent of each other, as shown in Fig. 1*. By this construction of the retaining-strip the lower edge of the shade is rendered flexible, and the whole is adapted to fold crosswise when the binding-strip is moved, while I am enabled to use short pieces of material, which obviously is economical.

What I claim as new, and desire to secure by Letters Patent, is—

1. The combination, with a window-shade, provided at its lower edge with a retaining strip or shoulder, as described, of a sheet-metal binding-strip, constructed to embrace the retaining strip or shoulder, substantially as for the purpose set forth.

2. The combination, with the shade, of retaining strip or shoulder and the detachable sheet-metal binding-strip, bent or shaped transversely to engage the retaining strip or shoulder, substantially as described.

3. The combination, with the shade, of fixed retaining-strip, constructed of independent sections, substantially as and for the purpose described.

In testimony whereof I have hereunto set my hand and seal in the presence of two subscribing witnesses.

PH. MICHEL. [L. S.]
